UNITED STATES PATENT OFFICE.

FRANK WYATT PRENTICE, OF TORONTO, ONTARIO, CANADA, ASSIGNOR TO THE PERRY-PRENTICE ELECTRIC COMPANY, A CORPORATION OF SOUTH DAKOTA.

RAILWAY SIGNALING OR TRAIN CONTROL.

1,105,923.

Specification of Letters Patent.

Patented Aug. 4, 1914.

Application filed March 27, 1911. Serial No. 617,699.

To all whom it may concern:

Be it known that I, FRANK W. PRENTICE, a citizen of the United States of America, residing in the city of Toronto, Dominion of 5 Canada, have invented certain new and useful Improvements in Railway Signaling or Train Control, of which the following is a specification.

The invention relates to railway signaling systems in which a generator of Hertzian waves is employed controlled by conditions of safety to propagate such waves and by conditions of danger to suspend the propagation of such waves and in which means 15 are provided at the place at which warning is given to indicate the presence or absence of such oscillations.

The object of my present invention is to devise reliable apparatus for the practical 20 operation of such a system, particularly to provide a thoroughly reliable receiving apparatus, and to provide means whereby a train proceeding cautiously under danger signals will not again receive indications of 25 safety on moving out of the block in which it received its warning into the next block, in which another train may be still located. I attain these objects and others which will 30 hereinafter appear by means of the constructions hereinafter described and illustrated in the accompanying drawings, in which—

Figure 1 is a diagrammatical view showing the track circuits of my system. Fig. 2 35 is a similar view showing the train circuits of my system. Fig. 3 is a detail of the coherer in transverse and in longitudinal section. Fig. 4 is an end view of the motor for oscillating the coherer.

40 In the drawings, like figures of reference indicate corresponding parts in the different figures.

In describing this system it will be best to first describe the train circuits as the 45 function of parts of the track circuits will be best understood after an understanding has been obtained of the train circuits.

One of the prime objects of the present invention is to keep a coherer 2 in constant 50 oscillatory rotary movement at the same time permitting sufficient dwell at the end of its movement in one direction to give sufficient time for the metallic particles in the

coherer to properly cohere. I accomplish this by the use of one or more relays, one 55 being shown in the drawings and lettered as 3. This relay is so wound that when the circuit through it is broken it will hold its magnetism for an appreciable time after the break occurs. This is accomplished by 60 winding only part of the core of the relay with wire, the remainder of the core being inclosed by a copper sleeve 5. This relay is used to make the contacts in the energizing circuit of a suitable motor device which oscillates the coherer, the result of the special construction of the relay being that when the circuit of the relay is broken it does not break the circuit which it controls until an appreciable time after, thus giving a dwell, 65 70 as hereinbefore referred to as being desired.

The wires 6 represent the circuit of the relay 3. 7 is the armature of this relay, which is suitably pivoted and carries the arm 8 adapted to actuate the contact finger 75 9 which makes and breaks the circuit 14 which includes the field winding 15 of a motor device. Between the poles of the motor device an armature 16 is rotatable, being carried by the shaft 11. 80

The coherer is shown as secured on a sleeve 108, loose on the shaft of the armature and is provided with the clamp 10, preferably of compressed fiber, by means of which the friction on the shaft may be 85 regulated to give the latter the desired frictional driving connection with the coherer. By this arrangement the rotation of the armature will elevate the coherer, but the armature is free to run on after the coherer 90 is stopped by contact with the stop 102. This arrangement effectually avoids all the troubles, electrical and mechanical which result, if the armature and coherer were rigidly secured together and the former therefore caused to stop as suddenly as the latter. A stop 103 is also provided to limit the downward movement of the coherer. An arm 12 is connected with the coherer, being shown as secured to the sleeve to which the 95 coherer 2 is connected. 100

One end of the circuit 6 of the relay 3 is connected with the contact finger 18 in the path of the end of the arm 12. This arm is thus adapted to make and break the circuit 105 of the relay 3 by being pressed against or

moved away from the finger 18. From this construction it follows that when the armature completes the circuit of the relay 3 that the relay is energized, closing the circuit of 5 and energizing the field 15 of the motor device. The armature is promptly rotated and the circuit of the first relay broken, but owing to the fact that the relay holds its magnetism for an appreciable time after its circuit is broken, the field circuit is not broken 10 until a sufficient time has elapsed to cause the armature to fully throw up the coherer which remains up till the armature loses its momentum. The metal particles of the coherer thus have plenty of time to properly cohere. In practice about one second of time is necessary for this purpose.

A weight 13 is connected to the coherer which is sufficient to cause the coherer to drop as soon as the momentum of the armature runs down. The dropping of the coherer causes de-coherence and also causes the arm 12 to again close the coherer circuit and re-energize the motor and once again 15 raise the coherer to the position in which coherence is possible. Now, as a circuit through the coherer is depended on to prevent the operation of signal receiving devices, it is necessary to provide means whereby 20 the circuits including these signal receiving devices, shall not be broken during such time as the coherer has its metal particles in a state of decoherence. I utilize for this purpose relays constructed substantially 25 as that hereinbefore described by which means I am enabled to hold the circuits of the signal receiving devices closed until such time as the coherer remains in its non-conductive state for a longer period than 30 that utilized under normal conditions for decoherence. This condition obtains only when a cessation occurs of the production 35 of the Hertzian waves which indicate a condition of safety.

The relay 19 is provided with a suitably arranged armature 21 which carries the arm 22 which is adapted to engage the contact finger 23 to make and break the circuit 24 of the third relay 25. This relay 25 is provided with a hinged armature 26 which carries the arm 27 which is adapted to engage the contact finger 28 to open and close the circuit 29 of the fourth relay 4. In series 40 with the fourth relay is the solenoid 67 of which 68 is the armature. This solenoid is provided with a tube core 69 which is connected with the whistle line 70. The valve seat 71 is formed in a partition in the whistle line and the stem 72 connected to the 45 armature 68 is shaped to engage this valve seat. As long as the solenoid 67 is energized the armature 68 will be held down and the whistle line valve will be held close. As soon, however, as the solenoid 67 is deenergized the valve will be opened, the whistle

line vented and the whistle caused to sound until the solenoid 67 is again energized. The fourth relay 4 is provided with the hinged armature 82 which carries the arm 83 which is adapted to engage the contact finger 84 to open and close the circuit 85 of the fifth relay 86. In series with this relay is the mechanism controlling the train pipe valve hereinafter described. By this arrangement of relays the train pipe valve circuit 85 is held closed until after the whistle has been sounded so that the engineer receives an audible warning before the train pipe valve is operated and the train brought to a standstill by the application of the air brakes.

The fifth relay 86 is provided with the hinged armature 87 which carries the arm 88 which is adapted to engage the contact finger 89 to open and close the circuit 90 of the sixth relay 91. This relay 91 is provided with the hinged armature 92 which carries the arm 93 which is adapted to engage the contact finger 94 to open and close the circuit 95 of the seventh relay 96. This contact finger 94 tends to engage the back contact 97 in the circuit 98 suitably connected with the circuit 85 of the mechanism controlling the train pipe valve. Thus this mechanism will be energized at such times as the relay 96 is deenergized. The relay 96 is provided with a hinged armature 99 which carries the arm 100 which is adapted to engage the contact finger 101 to move it into engagement with the contact 32. The spring of the finger will tend to keep it in contact with the back contact 33.

The particles in the coherer are always caused to cohere by the action of the Hertzian waves. These are received in the coherer circuit through the medium of certain antennae either the pick-up wire 30 or the supplemental pick-up or unlocking wire 31. It will be noted that the pick-up wire 30 is connected with the contact 32 while the unlocking wire 31 is connected with the contact 33. When the relay 96 is energized the finger 101 will be maintained in contact with the contact 32 so that waves are received through the pick-up wire 30 and led to the coherer circuit through the medium of the wire 81. When the armature is released as shown in the drawings the contact finger 101 will, by its natural spring, break contact with the contact 32 and will come into contact with the contact 33, so that waves may be received by the coherer circuit through the medium of the unlocking wire 31 being led into the coherer circuit through the wire 81 as before. The purpose of this arrangement is as follows:— Under normal conditions of safety waves are received through the medium of the pick-up wire 30 and the coherer made conductive, immediately after its de-coherence

through the operation of the motor mechanism. No waves under this condition will be received through the unlocking wire 31. Once, however, the pick-up wire fails to receive the waves, through the cessation of their generation, the apparatus assumes the position shown in the drawing when waves can no longer be received through the medium of the pick-up wire but only through the medium of the unlocking wire. This enables me to provide a safeguard, the necessity of which will appear after a consideration of the track diagram.

Referring to Fig. 1, 34 and 35 represent the double tracks of a railway line. These are divided into blocks, the rails in each block being insulated from one another, as indicated at 36. In each block a circuit 37 is provided, which includes the rails forming the track and a suitable source of energy such as 38. A relay 39 is included in the circuit and adapted to make and break a connection between the wave wire 40 and the secondary circuit of the oscillator 41, which is of ordinary construction. The primary circuit of the oscillator is energized through the medium of the alternating current mains 42, which will supply the oscillator of each block. The construction through which the relay 39 controls the connection between the wave wire 40 and the oscillator is as follows: A wire 43 is electrically connected with the rocking armature 44 of the relay, and this armature is adapted to engage the contact 49 in electrical connection with the secondary circuit of the oscillator. It will be noted that an auxiliary unlocking wave wire 45 is laterally offset relative to the wave wire 40 and extends substantially parallel thereto for a short distance at one end of the block. This unlocking wave wire is connected by the wire 46, with the armature 44, and the second contact 50 is preferably provided whereby the wire 46, and consequently the unlocking wave wire 45, may be brought into electrical connection with the secondary circuit of the oscillator. From this construction it will be seen that when the train enters the block that the track circuit 37 is short circuited, the relay 39 is consequently de-magnetized and its armature drops away, thus breaking the connection between the oscillator and the wave wires of the block behind. Any train then entering the block behind, while the other train is in the block ahead, will receive no oscillations, consequently the warning whistle is sounded and its train pipe valve opened. If the engineer elects to proceed, he may do so, as hereinafter described, with the warning constantly sounding. Supposing he does proceed and passes into the same block as the train ahead, he will (except for a special provision hereinbefore referred to, the

full purpose of which will now appear) again receive oscillations and might then proceed at full speed and run into the train ahead. The provision to which I have referred is the unlocking wave wire 45 of the track circuit and the unlocking wire 31 of the train circuit. These are so arranged that the pick-up wire will receive waves from the wave wire, while the unlocking wave and unlocking wave wire are sufficiently displaced laterally to co-operate only with one another, so that the unlocking wire will receive waves only from the unlocking wave wire. As already stated, as soon as the train ceased to receive oscillations, the receiving apparatus was conditioned to receive only through the unlocking wire, consequently when the train left the block in which it received communications of danger and entered the next block, it would not receive any waves from the wave wire but would have to proceed cautiously until it reached the unlocking wave wire of the second block, consequently if the first train was stalled in this block, the second train could only approach it very slowly and under perfect control. It will be noted that as soon as an energized unlocking wave wire is reached the train system picks up the wave again and the normal condition is restored, the system being again adapted to pick up waves from the main wave wires. This provision of the unlocking wave wire in the track circuit and the unlocking wire in the train circuit is of the utmost importance, as it absolutely prevents any indications of safety being received under the circumstances hereinbefore referred to.

As the system shown in a double track system, track circuits 51 are provided for the second track similar in every respect to the track circuits 37 of the first track. These track circuits 51 include relays 52 which control the admission of waves to the wave wires 53 and unlocking wave wires 54 of the second track in a precisely similar manner to that in which the relays 39 control their circuits. It will be noted, as arranged, that only as many oscillators are required as there are blocks, each oscillator supplying waves to the up-track of one block and the down-track of the adjacent block.

I do not desire of course to limit myself to the precise arrangement of the track circuits shown, as many variations might be made, the important point being the arrangement of the unlocking wave wires, as shown.

I have previously referred to the mechanism controlling the train pipe valve. This will be readily understood on reference to Fig. 2 of the drawings. 55 is an electro-magnet included in the circuits 83 and 98. A hinged armature 56 formed as a bent lever is provided for the electro-magnet. This

armature is provided with a spring-actuated latch 57 which is adapted to engage beneath the arm 58 formed on one part of the toggle 59, one end of which is pivoted on a stationary part and the other pivoted to a lever 60. This lever 60 is connected with a spindle 63 connected with a diaphragm 61 located in the train pipe 62 which represents the ordinary train pipe of an air brake system. The spindle 63 is also connected to a suitably fulcrumed lever 64 which is also pivotally connected at one end with the slide valve 65 controlling an outlet 66 to the atmosphere. It is evident that as long as the electro-magnet 55 is energized that the slide valve 65 will be held closed but when the electro-magnet is deenergized the slide valve will be opened by the pressure on the diaphragm and the train pipe pressure vented causing an application of the brakes. It will be noted that the plunger 74 of a solenoid 104 is connected with the toggle 59. This solenoid, as herein-after described, enables the engineer after the train pipe pressure has been sufficiently vented to restore the toggle to its normal position and thus again close the valve 65. The deenergizing of the electro-magnet 55 is caused by the deenergizing of the relay 4 and, since the following relays in the series successively become deenergized after the relay 4, the electro-magnet 55 is subsequently reenergized and the armature 56 restored to its normal position. The latch 57 is thus brought into position to reengage with the arm 58 and this reengagement takes place as soon as the engineer has, through the medium of the solenoid and its connections hereinafter described, restored the toggle to its normal position, the spring actuated latch 57 yielding to allow the end of the arm to pass and immediately thereafter resuming its normal position below the end of the arm.

The solenoid 104 is included in a circuit 45 105, one end of which is connected to the finger 89 and the other to the contact 106 with which the finger 89 tends to engage. A push button 107, or other suitable switch, is arranged in the circuit 105 within reach 50 of the engineer. Thus when the relay 86 is deenergized, the circuit 105 is completed at the contact 106 and may then be manually closed at the button 107 to energize the solenoid 104 and close the train pipe valve.

55 The arrangement above described permits the engineer to resume control of his train after it has been automatically stopped and to proceed slowly with the warning whistle on the whistle line 70 constantly sounding.

60 It may be advisable to briefly recapitulate the series of results following from the cessation of wave receiving by the train system. If the interruptions in the coherer circuit are due only to the normal decoherence of 65 the coherer caused by the operation of the

motor device, the first relay will probably be alternately energized and deenergized, but owing to the peculiar construction already described by which it is rendered sluggish in deenergizing and owing to the succeeding 70 relays being of similar construction, they will not break the circuits which they control and no warning signal will be sounded nor will the train pipe valve be operated. As soon, however, as the coherer circuit is 75 broken by its failure to receive any waves the relays will successively become deenergized. The result of this is that first of all a warning whistle is sounded. A second or two later the train pipe will be vented and 80 a second or two later than that the electro-magnetic controlling device for the train pipe operating means will be restored to its normal position allowing the engineer to restore the train pipe valve to its normal 85 position, as already described, if he wishes to do so. The position of the parts will remain as above outlined until waves are again received by the system which will, of course, as described, be through the unlocking wire 31. All the parts of the apparatus will then resume their ordinary working 90 positions.

95 It will be understood of course that each circuit will be supplied with current from any suitable source of current, such being diagrammatically illustrated in the drawings. I also wish it to be clearly understood that any form of relay arranged in any way to hold closed the circuit it controls an appreciable time after its own energizing circuit is broken, may be substituted for the specific form shown. Other forms of wave receiving devices might also be substituted for the coherer shown though I consider the 100 Branly coherer best adapted for the purpose. This will usually be arranged as shown in Fig. 3, a hole being formed in the fiber block 78 in which are placed the usual metal fittings. The hole is closed by a screw cap 79 105 and is provided with the lugs 80 to which the wires of the coherer circuit are connected. The oscillation of the coherer alternately brings the metal filings between the lugs and tips them out. The unlocking wave 110 wire may also of course be used with single track railway lines.

115 What I claim as my invention is:

120 1. In the train system of a railway control system using Hertzian waves the combination of a coherer; means for rocking the same to produce decoherence; a danger warning receiver; electric means controlling said danger warning receiver; a relay controlling the circuit of the said electric controlling means and in circuit with the coherer, and an antenna connected with the coherer circuit, the relay in the coherer circuit being of a sluggish type and thus adapted to hold closed the circuit of the danger 125 130

warning receiver an appreciable time after the coherer circuit is broken by the rocking of the coherer.

2. In the train system of a railway control system using Hertzian waves the combination of a coherer; means for rocking the same to produce decoherence; a danger warning receiver; electric means controlling said danger warning receiver; a series of relays the last relay controlling the circuit of the said electric controlling means and in turn controlled by the preceding relay, the first being in circuit with the coherer; and an antenna connected with the coherer circuit, the said relays being of a sluggish type and thus adapted to hold closed the circuit of the danger warning receiver an appreciable time after the coherer circuit is broken by the rocking of the coherer.

20 3. In the train system of a railway control system using Hertzian waves the combination of a train control and danger-warning system comprising a coherer; means for agitating the coherer to obtain de-coherence; a signal device, electromagnetic means for operating the signal device; a train pipe valve; electromagnetic means controlling said train pipe valve; a series of relays the first in circuit with the coherer and each controlling the circuit of the next succeeding relay, one relay controlling the signal operating means, a succeeding relay being adapted when energized to close the train-pipe valve controlling means, and a succeeding relay adapted when de-energized to close the circuit of the train-pipe valve controlling means.

4. In a railway control system using Hertzian waves a track system including a main and an auxiliary wave wire offset relatively to one another a train system comprising means adapted to receive waves from one only of said wires at any given time; and means controlled by said receiving means whereby the cessation of wave-sending from the main wave wire conditions the receiving means to receive waves from the auxiliary wave wire instead of from the main.

5. In a railway control system using Hertzian waves a track system including a main and an auxiliary wave wire offset relatively to one another a train system comprising means adapted to receive waves from one only of said wires at any given time; and means controlled by said receiving means whereby the cessation of wave-sending from the main wire conditions the receiving means to receive waves from the auxiliary wave wire instead of from the main, said means

being adapted to restore normal conditions 60 on the receiving of waves from the auxiliary wave wire.

6. In a railway control system, means for generating Hertzian waves; a track system including a main and an auxiliary wave 65 wire offset relatively to one another; a train system including means adapted to receive waves from one only of said wires at any given time; means controlled by said receiving means whereby the cessation of wave 70 sending through the main wave wire conditions the receiving means to receive waves from the auxiliary wave wire instead of the main; and means whereby the receiving of waves from the auxiliary wave wire restores the 75 receiving means to its normal condition of adaptability to receive from the main wire.

7. In a railway control system, means for generating Hertzian waves, a track system including a main and an auxiliary wave 80 wire offset relatively to one another; a train system including means adapted to receive waves from one only of said wires at any given time; means controlled by said receiving means whereby the cessation of wave 85 sending through the main wave wire conditions the receiving means to receive waves from the auxiliary wave wire instead of the main; and means whereby the receiving of waves from the auxiliary wave wire restores the 90 receiving means to its normal condition of adaptability to receive from the main wire, said receiving means including two separate antennæ co-operating each with one of the wave wires.

8. In a railway control system means for generating Hertzian waves; a track system including a main and an auxiliary wave wire offset relatively to one another; the receiving means of a train system, including 100 a single coherer, adapted to receive waves from one only of said wires at any given time; means whereby the cessation of wave sending through the main wire conditions the receiving means to receive waves from the auxiliary wave wire instead of the main; and means whereby the receiving of waves from the auxiliary wave wire restores the receiving means to its normal condition of adaptability to receive from the main wire, said 105 means including two separate antennæ co-operating each with one of the wave wires.

Signed by me at Toronto, Canada, this 15th day of November 1910.

FRANK WYATT PRENTICE.
